CLAIM

The ornamental design for a compact disc scale with oval display, as shown and described.

DESCRIPTION

FIG. 1 is a perspective view of my new scale design

FIG. 2 is a top view of my new scale design

FIG. 3. is a bottom view of my new scale design

FIG. 4 is a left side view of my new scale design

FIG. 5 is a right side view of my new scale design

FIG. 6 is a back side view of my new scale design

FIG. 7 is a front side view of my new scale design; and,

FIG. 8 is an open perspective view of my new scale design.
My scale design is characterized by a hinged case similar to a compact disc case with a weighing table in a circular shape with a unique depiction of a stylus head and arm similar to a record player and an oval-shaped LCD display that is framed with two ascending buttons on each side.
